(75) Inventor: **Mark S. Rodder**, Dallas, TX (US)

Primary Examiner—Holly H. Bayham
(74) Attorney, Agent, or Firm—Smith IP Services, P.C.

(73) Assignee: **Rodder Technologies, Inc.**, Dallas, TX (US)

(57) **CLAIM**

(**) Term: **14 Years**

I claim the ornamental design for the reversible asymmetric hanger for suspension of objects by means including wires, strips and loops, as shown.

(21) Appl. No.: **29/260,083**

(22) Filed: **May 18, 2006**

DESCRIPTION

(51) **LOC (8) Cl.** **08-05**

FIG. 1 shows an isometric view of the new design for a hanger apparatus;

(52) **U.S. Cl.** **D8/373**

FIG. 2 shows a first side view of the new design;

(58) **Field of Classification Search** D8/373,
D8/356, 366, 371; 248/339, 214-215, 493,
248/489

FIG. 3 shows a second side view of the new design;

See application file for complete search history.

FIG. 4 shows a third side view of the new design;

FIG. 5 shows a top side view of the new design;

FIG. 6 shows a bottom side view of the new design;

FIG. 7 shows the first side view of the new design in use,

with the third side adjacent a wall, and with multiple fasteners securing the hanger apparatus to the wall;

FIG. 8 shows the first side view of the new design in use,

with the third side adjacent a wall, and with a single fastener securing the hanger apparatus to the wall;

FIG. 9 shows a fourth side view of the new design in use,

with the second side adjacent a wall, and with multiple fasteners securing the hanger apparatus to the wall; and,

FIG. 10 shows the fourth side view of the new design in use,

with the second side adjacent a wall, and with a single fastener securing the hanger apparatus to the wall.

The broken line showing of a partial wall and bolts is included for the purpose of illustrating environment and forms no part of the claimed design.
